METHOD OF MAKING HAND TOOLS

Lester Raymond Ryan, Plymouth, Conn.

Application December 6, 1945, Serial No. 633,124

1 Claim. (Cl. 76—106)

1

This invention relates to new and useful improvements in the method of making hand tools.

The objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claim.

The present invention is applicable to various hand tools as items of cutlery and other devices, such as putty knives, screw drivers, etc. In the accompanying drawing the invention is illustrated in connection with a paring knife or similar item. However, it is to be understood that the invention is not limited to such an item but applies to various devices including a shank or blade and a handle.

In the drawing:

Fig. 1 is a plan view showing a blank adapted to be formed into a knife;

Fig. 2 is an end elevational view of the blank of Fig. 1;

Fig. 3 is a more or less diagrammatical view showing the blank of Fig. 1 being subjected to a forming operation in conventional forming tools;

Fig. 4 is an isometric view showing the blank as formed by the tools of Fig. 3;

Fig. 5 is a view somewhat similar to Fig. 3 but showing the next forming operation;

Fig. 6 shows the article as the same as formed by the tools of Fig. 5;

Fig. 7 shows a tool performing the final forming operation; and

Fig. 8 is an isometric view showing the completed knife.

Referring in detail to the drawing, at 10 is generally indicated a blank, later to be formed into a paring knife or the like. This blank comprises a single piece of metal and includes an elongated central portion or shank 11 and a pair of side or wing portions 12 and 13. Integral with portion 11 is an extension 14 here shown as in the form of a knife blade. It will be understood that the extension 14 may be in the form of any desired piece of cutlery or other tool, for example, a putty knife or the shank of a screw driver or the like.

Side portions 12 and 13 are shown as provided at spaced points along their longitudinal edges with small ears 15 and 16 respectively. While the portions 12 and 13 are integral with the interme-

2

diate portion or shank 11 they are adapted to be folded relative thereto as along the dotted fold lines 17, and in addition portion 12 is adapted to be folded as along the score lines 18 and 19 while the portion 13 is adapted to be folded along the score lines 20 and 21, all as will hereafter more clearly appear. Blank 10 is also provided with pairs of holes or recesses 22 and 23 respectively adjacent the inner portions of the wings 12 and 13.

Initial folding or formation of the portion of the blank 10 to be fabricated into a handle is accomplished by suitable tools which may be as outlined in Fig. 3. These tools would include a spring pad 24, a plunger 25 and pilots 26. As these tools are brought against the blank the latter is formed into the shape shown in Figs. 3 and 4. That is, the intermediate part 11 remains fixed, the wing or portion 12 is offset downwardly from the fold line 17 to provide a portion 27 and then is folded sharply on the score lines 18 and 19 to provide the intermediate portion 28 and the upwardly bent portion 29.

Thus, the wing 12 is formed into an open ended hollow trough-shaped member having upwardly diverging side portions. Wing 13 is treated similarly but made into a reverse formation in that it is bent on the fold line 17 to provide an upwardly inclining portion 30 and on the score lines 20 and 21 to provide the intermediate portion 31 and a downwardly diverging portion 32. Thus wing 13 becomes an inverted open ended hollow trough-shaped member with diverging side walls. The score lines 18 through 21 provide for the obtaining of sharp bends and fold lines 17 may be scored, if that is desired. Clearly the trough-shaped members need not have inclined side wall portions but may be generally U-shaped or wholly curved as in an arc of a circle or the like.

Next the formed piece of Fig. 4 may be treated as by the tools of Fig. 5 in which case the piece is positioned as shown at 33 by the broken lines. Then as the tool is closed the partly formed handle is further formed in that the wing 12 is folded over into a position at one side of the intermediate portion 11 while the wing 13 is folded to a position at the other side thereof, these folds taking place along the lines suggested by the dotted lines 17 in Fig. 1. Now the handle generally designated 34, is somewhat Z-shaped in transverse section as is clear from Figs. 5 and 6.

Having been formed into this Z-shape, the handle is now located between the tools 35 and 36 as in Fig. 7 and the formed side portions or wings 12 and 13 are pressed downward to bring

their intermediate sections 28 and 31 into parallel relationship with one another and with the portion 11. As such wing portions are located at opposite sides of portion or shank 11 the free edge of the wall portion 29 of wing 12 and the free edge of the wall portion 32 of wing 13 are brought down against the opposite surfaces of opposite edge portions of the shank 11 as clearly shown in Figs. 7 and 8. During this operation the small ears 15 and 16 may be bent into the openings 23 and 22 respectively so as to lock the wings 12 and 13 in the desired relation to portion 11.

During this final operation in the tools 35 and 36 the inner and outer end portions of the intermediate sections 28 and 31 of the respective wings are pressed inwardly at angles as at 37 and 38 so as to close the end portions of the complete knife handle now designated 39.

Stainless steel is a popular material for knife blades. With such material heat setting of the completed handle portions 40 and 41, formed from the wings 12 and 13, or welding of such portions might not be practical. In such cases the handle portions are locked in place by the folding over of the small ears 15 and 16 into the holes 23 and 22 respectively. The number or type of these ears is not important and in fact the ears may be caused to lap over to hold the handle sections in place without the provision of the openings 22 and 23.

It will be apparent that the handle of the invention may be formed on articles other than knives and, in fact, the handle may be formed on various articles of cutlery and other items such as putty knives, screw drivers, etc. The handle is made in three forming operations as suggested in the drawing and thus is inexpensive to manufacture. Further, since the handle is one piece with the shank or blade, the handle

will never work loose as is the case with riveted wooden handles and cemented handles of metal or plastic. As before suggested, the hollow handle sections 40 and 41 may be partly or wholly curved as in an arc of a circle, or they may have right angularly related outer portions and side wall, etc.

Having thus set forth the nature of my invention, what I claim is:

10. The method of making an article of the character described comprising providing a blank including an elongated shank portion having an extension at one end and a pair of wing-like portions one integral with each longitudinal edge 15 of said shank, providing each wing-like portion with ears spaced along its free longitudinal edge forming said wing-like portions into open-ended trough-like members having their open sides facing oppositely, then folding said trough-like 20 members into positions over opposite sides of said shank portion with the open sides of said members facing the shank portion, and clinching the ears of the respective members over portions of said shank to fasten the free longitudinal edge 25 portions of the members in place.

LESTER RAYMOND RYAN.
